UNITED STATES PATENT OFFICE.

JOHANN FRANZ EDWARD WOLDEMAR SCHMIDT, OF DRESDEN, GERMANY.

REGENERATIVE-BURNER LAMP.

SPECIFICATION forming part of Letters Patent No. 415,067, dated November 12, 1889.

Application filed July 8, 1889. Serial No. 316,801. (No model.)

To all whom it may concern:

Be it known that I, JOHANN FRANZ EDWARD WOLDEMAR SCHMIDT, a subject of the Emperor of Germany, residing at Dresden, 5 in the Empire of Germany, have invented new and useful Improvements in Regenerative-Burner Lamps, of which the following is a specification.

The downwardly-radiating lamps of the 10 Wenham type, comprising pendent burners arranged in globes, are unsatisfactory in that the room and ceiling above the lamp are not illuminated by the light, and to avoid the disagreeable impression arising from the 15 darkness or gloom over the lamps the latter are necessarily arranged as near the ceiling as possible. This is objectionable, as it is difficult or inconvenient to reach the lamps, while the lights are placed at an undesirable 20 and often unsuitable distance from persons reading, writing, and the like. These objections are avoided by providing the burner-globe with a surrounding shade-globe of 25 translucent material having an air-inlet orifice in its bottom wall, whereby rays of light are dispersed toward the ceiling, and ascending air-currents caused to pass between the two globes, as in my application for Letters Patent filed January 21, 1889, Serial No. 30 297,031, patented July 30, 1889, No. 408,197.

The object of my present invention is to improve my prior construction and provide for an enlarged and more desirable illumination of the room and ceiling above the lamp, 35 which I accomplish in the manner and by the means hereinafter described and claimed, reference being had to the accompanying drawings, in which—

Figure 1 is a side elevation of a downwardly-radiating lamp, showing the shade-globe and retaining-ring in section; and Fig. 2 is a similar view showing the shade-globe in side elevation.

In order to enable those skilled in the art 45 to make and use my invention, I will now describe the same in detail, referring to the drawings, wherein—

The numeral 1 indicates an inverted pendent burner, 2 a circular flange on the lamp-frame 3, and 4 the transparent burner-globe having imperforate side and bottom walls, 50 and in which the pendent burner is located.

The shade-globe 5 incloses the burner-globe, and is suspended from the lamp-frame by a retaining-ring 6, resting on the flange 2, and 55 having hooked fingers 7, engaging a laterally-projecting flange 8 at the top of the shade-globe, the same as, or substantially the same as, in my application before alluded to.

The shade-globe is of a novel construction 60 for enlarging the circle of light and more effectually dispersing the rays of light to increase the illumination of the ceiling. For these purposes and to produce the desired softening of the downwardly-radiating light 65 I construct the shade-globe of transparent glass or other material, and cover, coat, or otherwise provide the outside of the lower half, or substantially the lower half, with a translucent substance or material—such as 70 milk-glass or ground glass—as at 9, such substance or material extending continuously and annularly around the shade-globe from at or about the horizontal axis or line 10 of the latter to the edge 11 of the unobstructed 75 air-inlet orifice in the bottom wall of the shade-globe. By this means the smooth transparent glass surface of the inside of the shade-globe below the axis or line 10 becomes a weak reflector that causes the 80 downwardly-radiating rays 12 from the flame to be reflected into a greater number of rays, as at 13, 14, and 15, which radiate upwardly and effectually illuminate the room above the lamp. The shade-globe curves laterally from the inner part of the top flange 8 in an outward direction considerably beyond the lamp-frame, such outward curve extending from the said flange 8 to the axis or line 10, or, rather, to the upper edge of the 85 coating or covering 9, of translucent material. From the axis or line 10 the globe uniformly curves around inwardly and upwardly toward the burner-globe, such curve terminating at the edge 11 of the air-inlet orifice and forming 90 a concavity from 10 to 11. The rays cast from the flame upon the smooth concave mirror or reflector are by the latter refracted into a greater number of rays to illuminate the room above the lamp, while some parts of the 100 rays radiate downwardly to illuminate the room below the lamp, whereby I obtain an approximately equal illumination of all parts of the room within the circle of the light.

Having thus described my invention, what I claim is—

1. The combination, with a lamp-frame, a burner-globe, and a pendent burner therein, of a suspended shade-globe of transparent material curved from its upper edge portion toward the burner-globe and having the lower portion of its external surface provided with translucent material to form an internal weak reflector that refracts the downwardly-radiating rays from the flame into a greater number of rays to illuminate the room above the lamp, substantially as described.
2. The combination, with a lamp-frame, a burner-globe, and a pendent burner therein, of a suspended shade-globe comprising a curved transparent upper portion and a concavo-convex translucent lower portion, forming an internal weak reflector which refracts the downwardly-radiating rays into a greater

number of rays to illuminate the room above the lamp, substantially as described.

3. The combination, with a lamp-frame, a pendent burner, and a burner-globe having an unobstructed air-inlet opening in its bottom wall, of a shade-globe curved laterally outward beyond the lamp-frame from its upper edge to or near its horizontal axis and then curved around inwardly and upwardly toward the burner-globe from its said horizontal axis to the edge of the said inlet-opening, substantially as described.

In testimony whereof I have affixed my signature in presence of two witnesses.

JOHANN FRANZ EDWARD
WOLDEMAR SCHMIDT.
